UNITED STATES PATENT OFFICE.

FRANK L. CROSS, OF MYSTIC, CONNECTICUT, ASSIGNOR TO AMERICAN PAPER FEEDER COMPANY, OF BOSTON, MASSACHUSETTS, A CORPORATION OF MAINE.

SHEET-REGISTERING MECHANISM.

SPECIFICATION forming part of Letters Patent No. 763,160, dated June 21, 1904.

Application filed July 12, 1902. Serial No. 115,310. (No model.)

To all whom it may concern:

Be it known that I, FRANK L. CROSS, of Mystic, in the county of New London and State of Connecticut, have invented certain new and 5 useful Improvements in Sheet-Registering Mechanism, of which the following is a specification.

This invention relates to sheet-registering mechanism for use in printing, folding, and 10 other sheet-handling machines to bring the sheets accurately into position with relation to the mechanism for acting thereon.

In practicing the invention the sheet is brought into position with its edge against a 15 fixed gage by the action of a reciprocating gripper, one of whose jaws is a roll. With this construction of gripper the pressure between the jaws of the gripper may be accurately adjusted to grip the sheet with sufficient force to start and move the sheet against the gage, and when the movement of the sheet is arrested by the gage the roll will turn to allow the gripper to move relatively to the sheet without crumpling the edge against the 25 gage. The frictional resistance offered by the roller-jaw to the movement of the gripper relatively to the sheet after it strikes the fixed gage depends upon the friction on the bearings of the roller, and consequently no 30 variations in the pressure between the gripper-jaws is required in acting upon different qualities of paper, as would be the case where the frictional resistance to relative movement between a gripper and sheet varied with the 35 character of the surface of the sheet.

The various features of the invention will be understood from the following detailed description of the mechanism in which I have embodied them and will be pointed out in the 40 claims.

In the drawings, Figure 1 is a plan view of so much of a machine for feeding sheets to the front gages of a printing-press as is necessary to show one application of the present 45 invention. Fig. 2 is a side elevation of the same. Fig. 3 is side elevation of the devices for acting on the sheet. Fig. 4 is a similar

view with the parts in a different position. Fig. 5 is a front elevation of the same, and Fig. 6 is detail. 50

In the drawings the features of invention are shown embodied in mechanism for effecting the side register of the sheets fed to a printing-press.

A indicates the feed table or guides, over 55 which the sheets are fed into position in front of the front guides or gages B of the press. After a sheet has come to rest with its front edge resting against the gages B it is acted upon by the side register devices, which move 60 it laterally into the proper position to be seized by the grippers or other sheet-carrying devices of the printing-press. The lateral position of the sheet is accurately determined by a fixed gage C, against which the edge of 65 the sheet is drawn by a reciprocating gripper, the jaws of which slip over the sheet when the edge engages and is arrested by the fixed gage. The fixed gage C is formed on a plate C', mounted to slide in a transverse slot 70 A', formed in the table A, so that the position of the gage may be adjusted as desired, and the plate is clamped in its adjusted position by a clamping-plate C² and thumb-screw C³.

The gripper for drawing the edge of the 75 sheet against the fixed gage consists of a lower jaw D, arranged to slide in a groove C⁴, formed in the plate C', and an upper jaw D', movable to and from the lower jaw, consisting 80 of a roll D. The jaws are carried by a bracket D², adjustably secured upon a reciprocating bar E extending transversely above the table A. The jaw D is in the form of a rigid finger extending laterally from the lower end of the bracket, while the jaw D' is carried by a lever 85 D³, pivoted on a stud D⁴, secured in the bracket. The pivoted jaw D' is pressed toward the stationary jaw D by a torsional spring D⁵, one end of which is connected to the lever D³ and the other end of which is 90 connected with a collar D⁶, mounted on the stud D⁴. The collar is held from rotation by a pin D⁷, which engages notches D⁸ in the collar. The tension of the spring may be ad-

justed by pressing the collar inward to disengage the pin and then turning the collar and reengaging the pin with the notches.

On the forward stroke of the gripper the 5 jaw D' is held away from the jaw D against the tension of the spring D⁵ by a latch D⁹, which engages a recess D¹⁰ in the rear end of lever D³. The latch is in the form of a roll carried by a lever D¹¹, pivoted to bracket D². 10 As the gripper reaches the end of its forward movement a pin D¹² on the lever D¹¹ strikes a stop C⁶, adjustably secured on plate C', and is swung back. This releases the lever D³ and allows the spring D⁵ to operate the jaw D' to 15 grip the sheet which lies between the jaws D and D'. The gripper is now retracted. As the gripper starts back the resistance of the sheet tends to rotate the roller-jaw D', and this tendency is resisted by the friction on 20 the roller-bearing. This friction is sufficient to prevent rotation of the roll, so that the sheet is moved with the gripper until its edge strikes the gage C. When the movement of the sheet is thus arrested, the frictional resistance to the rotation of the roller-jaw is overcome and the gripper continues its movement, leaving the sheet with the edge resting snugly against the gage. As the gripper reaches the 25 limit of its rearward stroke the lever D¹¹ strikes a fixed stop C⁶, swinging the lever forward. As the lever swings forward the roll D³ acts against the inclined cam-surface D¹³ on the lever and swings the rear end of the lever downward until the roll enters the recess D¹² and latches the lever in position with jaw D' raised preparatory to the next forward 30 stroke.

I prefer to so construct the fixed gage that it extends on both sides of the gripper, and 40 this I do by providing the gage with a slot C', through which the gripper reciprocates. The most efficient action is also obtained, especially when acting on their sheets, by having the slot just wide enough for the passage of 45 the gripper-jaw.

The edge of the sheet may be stiffened to 50 avoid danger of crumpling or bending the edge of a thin sheet by its engagement with the fixed gage by forming a transverse buckle or bend in the edge of the sheet. To accomplish this, I recess the lower jaw D and form the upper jaw D' to enter the recess. I also provide a buckling-plate D¹⁴ back of the roll for coöoperating with the jaw D and roll D' in 55 forming the bend or buckle in the sheet. This feature is of especial importance in acting upon thin and soft paper, but may be omitted in cases where the paper is sufficiently stiff to resist the drawing action of the grippers 60 without bending.

Where, as in the application of the invention shown, the sheet is fed into position in front of the fixed gage in a direction at right angles to the movement of the gripper, I pre-

fer to so arrange the gripper that when retracted it will be at one side of the path of the sheet, as indicated in Fig. 3. With the gripper thus arranged it cannot interfere with proper movements of the sheets and requires no special construction or devices for insuring the entrance of corner and edge of the sheet between the gripping-jaws as the sheet is fed into position. In case the sheet is fed into position in front of the fixed gage in a direction parallel to the movement of the gripper 75 the location of the gripper with relation to the edge of the sheet during the feed of the sheet is not of so much importance.

The bar E may be reciprocated by any suitable mechanism; but I prefer to employ for 80 this purpose a simple and efficient mechanism which I have devised and which is shown in Figs. 1 and 2. This mechanism consists of a spiral segment E', arranged to engage a spiral rack E², formed upon the end of the bar E. 85 The bar is guided in bearings E³, and as the segment E' is oscillated the bar is reciprocated in a direction parallel to the axis of the segment. The segment is oscillated from a rock-lever E⁴, which is operated from any suitable 90 moving part of the machine through a connecting-rod E⁵. The rock-lever is connected with the segment by a link E⁶, one end of which is connected to the segment and the other end of which is connected to a jaw E⁷ 95 on the rock-lever.

To enable the sheets to be registered at either side of the table A, two sets of registering-grippers are provided, the set which is out of use being turned up out of the way, as shown 100 in Fig. 1. In changing the register from one side to the other the timing of the reciprocating bar E must be reversed. To enable this to be done quickly and conveniently, I provide the rock-lever E⁴ with two pins E⁷, arranged diametrically opposite each other. By shifting the end of the connecting-link E⁶ from one pin to the other the timing of the movement of the bar E will be reversed.

What I claim, and desire to secure by Letters Patent, is—

1. In a sheet-registering mechanism the combination of a fixed gage, a reciprocating gripper one of whose jaws is a roll, means for advancing the gripper to grasp the sheet and for retracting the gripper to carry the edge of the sheet against the gage, substantially as described.

2. In a sheet-registering mechanism the combination of a fixed gage, of a reciprocating gripper comprising a fixed jaw and a roll movable to and from said jaw, and means for operating said gripper to grasp the sheet and draw it against said gage, substantially as described.

3. In a sheet-registering mechanism the combination of a fixed gage, and a reciprocating gripper comprising a recessed jaw, a roll

movable to and from said jaw, and a buckling-plate in the rear of said roll, substantially as described.

4. In a sheet - registering mechanism the combination of a fixed gage, a reciprocating gripper comprising a fixed jaw, a pivoted spring-operated jaw, a latch for said pivoted jaw, a stop for tripping said latch on the forward stroke, and a stop for engaging said latch on the return stroke, substantially as described.

5. In a sheet - registering mechanism the

combination with a reciprocating bar of devices for engaging the sheets carried by said bar, a spiral rack on said bar, and an oscillating spiral segment engaging said rack, substantially as described. 15

In testimony whereof I have affixed my signature in presence of two witnesses.

FRANK L. CROSS.
